UNITED STATES PATENT OFFICE.

ALBERT E. GRANT, OF NEW YORK, N. Y.

OIL STRAINER.

Application filed June 10, 1927. Serial No. 197,835.

My invention relates to strainers for oil used in oil burning systems, etc.

The object of my invention is to provide a strainer having a large capacity considering the size of the casing, and also to provide a casing that can be separated to remove the mesh or filtering elements without disconnecting the pipes leading to and from the casing, and without spilling any oil, the construction being such that the oil may be shut off from the lower part of the casing containing the strainers, and the strainers freely removed for cleaning without difficulty.

Referring to the drawings forming a part 15 of this specification:

Figure 1 is an elevational view, shown partly in section, of a strainer embodying my invention.

Figure 2 is a plan view of the strainer.

Reference character A indicates the top portion of the casing and B, the bowl portion, each of which is provided with a flange A¹ and B¹ respectively. A packing ring C, serves to form a tight joint between the flanges, and the flanges are secured together in separable relation by screws or bolts D—D, etc.

The top portion of the casing is provided with an inlet E and an outlet E¹. A bore or chamber F, is formed in the top A, in open communication with the outlet E¹, and a passage G leads from the bowl to the chamber F, the lower end of said passage opening into the bowl near one side thereof as shown. The top end of the chamber F, is closed by a cap plug H which is provided with a valve face H¹ which fits a valve seat H², formed in the wall of the chamber to provide a metal to metal joint at this point. The plug H is provided with a central threaded bore H³, and with a valve seat H⁴, at its lower end, and a valve stem I, is threaded to fit the thread in the bore H³. The valve-stem is provided with a square formed end I¹, for engagement 45 with a wrench to screw the stem I in operating the valve I², formed integral with the stem, to its seat J, formed in the bottom of the chamber F, and controlling the passage G. The stem is also provided with a conical face I³ which fits the seat H⁴, to prevent leakage by the stem when the valve I² is open. A similar valve-stem, valve, and seats, etc., is located in the housing portion K, to that just described, and its passage from the

valve-chamber is indicated by L, and leads 55 within the upper end of a gauze strainer M, which is cylindrical in form and open at both ends.

The under side of the top portion is provided with a circular depending flange portion N, formed integral, and corresponding flanges N¹ are formed integral with the bottom of the bowl.

The length of the cylindrical strainers M—M respectively, is such that they abut 65 and are clamped tightly against the side surfaces of the flange portions N and N¹ when the bowl B is secured to the top portions of the casing by the screws D.

The inner strainer is of coarse mesh relative to the outer strainer, so that their straining capacity is about equal.

The strainers are made of metal gauze from a sheet, the sheet being formed into cylindrical shape and the side seam is strongly soldered as illustrated at O, and each end is dipped in solder to provide a re-inforcement and a smooth surface for contact with the flanges, as illustrated at O¹ and to provide tight joints at the abutment points.

Oil is very hard to hold as it seeps thru the joints unless they are formed properly, and by using metal to metal valve seats I find I can prevent such leakage.

In operation, the valves being open, the oil flows thru the inlet to the inlet chamber and thru passage L into the space P, and thence thru the strainers to the space P¹ and out thru the passages G and E¹ to the pipes connected therewith.

To remove the strainers to clean etc, the valves I² are closed, after which the bowl is disconnected from the top, when the strainers may be freely removed without spilling any oil, since the depending flange portion Q, extends into the top of the bowl far enough to prevent overflow of the oil in the bowl when same is lowered relative to its top portion, as will be readily understood.

Having thus described my invention, I 100 claim as new:

1. A strainer comprising an upper valve casing portion and a lower bowl portion, said upper portion having a depending part which extends into the upper end of the bowl 105 to reduce the fluid capacity of the bowl; said upper portion having a valve controlled inlet passage and a valve controlled outlet passage,

and a strainer in said bowl in the line of flow of a fluid passing therethru, and means for connecting the bowl to the upper portion in separable relation therewith.

- 5 2. A strainer comprising an upper valve casing portion and a lower bowl portion connected thereto in separable relation therewith, said upper portion having an inlet passage leading to the bowl and an outlet passage 10 leading therefrom, a strainer in said bowl in the line of flow of a fluid passing from the inlet to the outlet passage, a cap-plug having a central threaded bore with a valve-seat formed at its lower end and a valve-stem 15 having a valve for controlling one of said passages and also provided with a valve face to abut the valve-seat formed on the cap-plug, said upper portion having a depending part which extends into the upper end of the bowl 20 to reduce the fluid capacity thereof.

3. A strainer comprising an upper valve casing portion and a lower bowl portion connected thereto in separable relation therewith, said upper portion having an inlet passage 25 leading to the bowl and an outlet passage leading therefrom, a strainer in said bowl in the line of flow of a fluid passing from the inlet to the outlet passage, a cap-plug having a central threaded bore with a valve-seat 30 formed at its lower end and a valve-stem having a valve for controlling one of said passages and also provided with a valve face to abut the valve-seat formed on the cap-plug and a duplicate construction carried by said 35 upper part for controlling the other of said passages, said upper portion having a depending part which extends into the upper end of the bowl to reduce the fluid capacity thereof.

- 40 4. A strainer comprising an upper valve casing portion and a lower bowl portion, said upper portion having a valve controlled inlet passage and a valve controlled outlet passage, and a strainer in said bowl in the line of flow of a fluid passing therethru, and means for connecting the bowl to the upper portion in separable relation therewith, said strainer comprising a cylindrical gauze mesh, the ends of which are reinforced by soft 45 metal such as solder.

5. A strainer comprising an upper valve

casing portion and a lower bowl portion, said upper portion having a depending part which extends into the upper end of the bowl to reduce the fluid capacity of the bowl, said upper portion having a valve controlled inlet passage and a valve controlled outlet passage, and a strainer in said bowl in the line of flow of a fluid passing therethru, and means for connecting the bowl to the upper portion in separable relation therewith, said strainer comprising two cylinders of gauze mesh of relatively different diameters, the cylinder having the coarser mesh being located within the larger cylinder. 65

6. A strainer comprising an upper valve casing portion and a lower bowl portion, said upper portion having a depending part which extends into the upper end of the bowl to reduce the fluid capacity of the bowl, said 70 upper portion having a valve controlled inlet passage and a valve controlled outlet passage, and a strainer in said bowl in the line of flow of a fluid passing therethru, and means for connecting the bowl to the upper portion 75 in separable relation therewith, said strainer comprising two cylinders of gauze mesh of relatively different diameters, the cylinder having a coarser mesh being located within the larger cylinder and spaced therefrom, and 80 located adjacent the outlet of the inlet passage leading to the bowl.

7. A strainer comprising an upper valve casing portion and a lower bowl portion, said upper portion having a depending part which 85 extends into the upper end of the bowl to reduce the fluid capacity of the bowl, said upper portion having a valve controlled inlet passage and a valve controlled outlet passage, and a strainer in said bowl in the line of flow 90 of a fluid passing therethru, and means for connecting the bowl to the upper portion in separable relation therewith, the under side of said upper portion having a depending circular flange formed thereon, and the upper 95 side of the bottom of said bowl having a corresponding flange, the ends of said strainer being held in abutting engagement between said flanges.

In testimony whereof I have affixed my signature.

ALBERT E. GRANT.
